W. H. ALLEN.
CHIME ATTACHMENT FOR CLOCKS.
APPLICATION FILED FEB. 18, 1919.

1,426,806.

Patented Aug. 22, 1922.

UNITED STATES PATENT OFFICE.

WILLIS H. ALLEN, OF SYRACUSE, NEW YORK.

CHIME ATTACHMENT FOR CLOCKS.

1,426,806.

Specification of Letters Patent. Patented Aug. 22, 1922.

Application filed February 18, 1919. Serial No. 277,808.

To all whom it may concern:

Be it known that I, WILLIS H. ALLEN, of Syracuse, in the county of Onondaga, in the State of New York, have invented new and useful Improvements in Chime Attachments for Clocks, of which the following, taken in connection with the accompanying drawings, is a full, clear, and exact description.

This invention relates to chime attachment for clocks, the main object being to enable it to be applied to standard forms of clocks without material alteration or interference with the free operation thereof in the usual manner.

In other words I have sought to provide a chime mechanism as a unitary article of manufacture capable of being easily and quickly attached to the frame of a standard form of clock as an extension thereof, so as to operate under its own motive power independently of that of the clock, thereby relieving the clock from any additional load which may be necessary to operate the chimes.

Another object is to control the operation of the chimes by means of escapement mechanism forming a part thereof, and adapted to be released at regular predetermined intervals through the medium of a clock actuated tripping device.

A further object is to provide means whereby the periods of continuous operation of the chimes vary for different fractions of each hour of time, as for example, a relatively short period at the end of the first quarter, twice that period at the end of the second quarter or half hour, three times that period at the end of the third quarter, and four times that period at the end of the fourth or last quarter.

A still further object is to provide means whereby the individual sound producing devices may be operated in sequence in different combinations for the several periods.

Other objects and uses relating to specific parts of the chiming attachment and its controlling means will be brought out in the following description.

In the drawings—

Figure 1— is a rear elevation of a standard type of clock frame and train, showing my improved chime mechanism attached

thereto, and in operative connection with the tripping device for the escapement mechanism.

Figure 2— is an enlarged transverse vertical sectional view of the detached chime mechanism taken on line 2—2, Figure 1—, showing the vibratory sound producing rod and strikers therefor, and also the hour spindle and hand of the clock, together with the tripping device for the escapement of the chime mechanism.

Figure 3— is a vertical sectional view taken in the plane of line 3—3, Figure 2—.

Figure 4— is a detail sectional view taken on line 4—4, Figure 2—.

In order that the application of my invention may be clearly understood I have shown a portion of a standard type of clock comprising a main frame 1—, a gear train 2— including a minute shaft 3— and its hand 4—, and spring motors 5—, the action of the clock train by the motors being controlled by the usual governor and escapement mechanism not necessary to herein illustrate or describe.

The chime mechanism which constitutes an attachment for the clock comprises a suitable frame 6—, rigidly secured by 7— to the lower portion of the clock frame 1—, so as to constitute an extension of the base thereof, and is adapted to receive and support a gear train 8—, and a spring motor 9—, an escapement mechanism and tripping means therefor, hereinafter described, together with a series of in this instance four chime bars 10—, strikers 11—, and suitable operating and controlling mechanism therefor.

The chime bars 11— are disposed in the same forwardly and rearwardly extending plane, preferably at the rear of the frame 6—, and clock frame 1—, and of different length gradually diminishing rearwardly for producing different tones, their lower ends being rigidly secured to a suitable support 12—, which in this instance is clamped by the pivoted bolt 13—, to the rear plate of the frame 6— to permit all 100 of the chime bars to be properly adjusted relatively to their respective hammers or strikers 11—, for producing the desired tones when struck by the hammers, said

chime bars being preferably inclined upwardly and laterally from their support —12— and are spaced a sufficient distance apart to permit their free vibration independently of each other, as shown more clearly in Figure —2—.

The heads of the hammers or strikers —11— are mounted upon separate spring arms or wires —14— so as to engage the chime bars in approximately the same horizontal plane near the upper ends thereof, the lower ends of the spring wires —14— being offset laterally and downwardly to form heel extensions —15—, which are secured in separate rock arms —16—, and are adapted to engage a stop —17— for limiting the throw of the hammer heads toward the chime bars, and normally holding the strikers slightly out of contact therewith, relying upon the resiliency and momentum of the strikers to strike their respective bars when the strikers are retracted in a manner presently described.

The rock arms —16— are pivoted at —18— to the frame —6— some distance to one side of the plane of the chime bars —10—, while the centers of gravity or weight of the main body of the strikers are between the pivots —18— and chime bars to cause the strikers to move under their own weight toward their striking positions after being retracted.

The means for retracting the strikers comprises a series in this instance of four coaxial toothed wheels —19— mounted end to end upon one and the same rotary shaft or spindle —20—, one for each striker, each wheel being provided with a series of peripheral teeth —21— adapted to engage the heel of its corresponding rock arm —16— for operating the companion striker one or more times during each revolution of the shaft —20—, the teeth of the several wheels being preferably arranged in staggered relation lengthwise of their axis, so as to appear in end view in uniformly relation circumferentially.

This circumferentially spaced relation of the teeth —21— causes sequential or successive operation of the strikers and their corresponding chime bars or when the same wheel is provided with more than one tooth, as shown in Figure —4—, the operation of the corresponding striker will be repeated at intervals corresponding to the circumferential spacing of the teeth, those of the several wheels being arranged to produce harmonious tones in various sequential combinations, but preferably to give distinctive sounds for each quarter of the hour as will be hereinafter more fully explained.

The shaft —20— is driven by the gear train —8— and is provided with a pinion —22— meshing with a gear —23— which is loosely mounted on a stud or bearing —24—

on the rear plate of the frame —6—, and to which is secured a coaxial stop wheel —25— for rotation therewith.

The stop wheel —25— is provided with a plurality of in this instance four peripheral notches —a— b— c— d— spaced gradually increasing distances apart from the first notch —a— in a direction opposite to that of its rotation, as indicated by the arrow —X—, Figure —3—, and corresponding in effect to the first quarter, second quarter, third quarter, and last quarter of each hour of time respectively.

That is, the space between the notch —a—b— is the shortest, while the length of the remaining spaces successively are in the proportion of 2, 3, and 4 times as long as the first named space, and serve in a manner presently described to vary the periods of continuous operation of the chimes for the several fractions of the hour as above outlined.

A pawl or detent —26— is pivoted at —27— to the frame —6— to rock into and out of engagement of the notches —a— b— c— and —d— against the action of a retracting spring —28—, and when engaged in either said notches serves to hold the entire gear train at rest against the action of the motor —9—.

Suitable clock actuated means is provided for tripping the detent —26— at the end of each quarter hour, and for this purpose is provided a tripping lever —29— pivoted at —30— to the frame —6—, and having one end extended upwardly through the clock frame —1— to a point in proximity to the minute shaft —3— of the clock, said shaft being provided with a cam or tripping wheel —31— having a plurality of in this instance four arms —32— spaced uniform distances of substantially 90° apart circumferentially, and adapted to successively engage an off-set —33— at the upper end of the tripping lever —29—, as the cam wheel —31— is rotated in the direction indicated by arrow —Y—, Figure —3—.

This tripping lever —29— extends across the detent —26— between its point of engagement with a notched wheel —24— and pivot —27— and is provided with a lateral off-set —34— directly under a curved cam portion —35— of the detent so that when the tripping lever —29— is rocked about its pivot —30— by one of the arms —32— of the cam wheel —31— the off-set —34— will ride against the cam portion —35— and trip the detent —26— from holding engagement in either notch of the wheel —24—, thereby permitting said wheel to be rotated by the motor —9— through the medium of the gear train —8— of which the pinion —22— and gear —23— forms a part.

In order that the detent —26— may operate freely without excessive friction with

the walls of the notches of the wheel —24— I have provided an escapement mechanism consisting of a pin —36— on one of the gear wheels as —37— of the train —8— to 5 co-operate with supplemental detent —38— which in this instance forms a continuation of the detent —26— in that it is secured to the same rock shaft or pivot —27— to move simultaneously with said detent —26—.

10 The free end of the supplemental detent —38— is off-set downwardly and normally rests in the path of and against the pin —36— when the detent —26— is in one or 15 the other notches of the wheel —25—, as shown in Figure —3—, so that when the tripping lever —29— is operated by the cam wheel —31— of the clock mechanism it will trip both of the detents —26— and —38— simultaneously to permit the operation of 20 the gear train —8— by the motor —9— for operating the striker controlling wheels —19—.

The speed of movement of the gear train —8— is controlled by a governor —39— 25 while relative ratios of companion gears are such that the movement of the gear —23— and its notched disc or wheel —25— is relatively slow as compared with that of the gear —37— carrying the stop pin —36—, 30 and in order to avoid any possibility of re-entrance of the detent —26— into the same notch from which it has just previously been withdrawn by the operation of the lever —29—, I have provided a catch lever 35 —40— which in this instance is a continuation of the tripping lever —29—, and secured to the same rock shaft or pivot —30—, the free end of said catch lever being provided with an upturned stop shoulder 40 —41— which is movable into the path of the stop pin —36— simultaneously with the release of both detents —26— and —38—, at which time the notch —2— will have 45 been moved a slight but sufficient distance beyond the engaging point of the detent —26— to prevent re-entrance of the latter into the notch immediately following release of the tripping lever —29—.

It will be observed that immediately upon 50 the passage of the point of either of the arms —32— beyond the off-set end —33— of said lever, allows said lever to return to its starting position, as shown by full lines, Figure —3—, which in turn rocks the 55 catch lever —40— from its holding position, and thereby frees the detents —26— and —38—.

It is evident that these detents cannot return to their normal position until 60 the next succeeding notch —b— is registered with the free end of the detent —26— by reason of the fact that it rides upon the periphery of the wheel —25—, between said notches, but when the notch —b— is registered with the free end of the detent

—26—, the latter will drop thereinto to stop further movement of the gear train —8—.

During this operation of the gear train the toothed wheels —19— serve to operate the strikers —11— against their respective 70 chime bars —10— to produce the desired tones.

The relative positions of the detents —26— and —38— and also the catch lever —40— are so arranged with reference to 75 the speed of movement of the wheels —25— and —37— as to cause the stop pin —36— to engage its detent —38— at about the same time that the detent —26— enters either of the notches in the wheel —25—, but I do 80 not wish to limit myself to the use of the levers —38— and —40— and stop pin —36—, since it is believed to be possible to continue the entire operation of the strikers 85 at the proper time and for the desired period through the medium of the detent —26— and tripping lever —29— as the later is controlled by the cam wheel —31— of the clock mechanism.

Since the cam wheel is rotated one complete revolution each hour and its arms —32— are spaced equally apart it is evident that the tripping lever —29— will be operated once each quarter hour, thus permitting the operation of the gear train and 90 chimes at the end of each of those intervals, and in order that the chimes for one interval may be distinguished from those of another interval the successive periods of continuous operation are gradually increased through the four quarters of each hour, the period of operation at the end of the first quarter being the shortest, and that at the end of the last quarter being the longest as controlled by the progressive 100 increasing distances between the notches in the periphery of the disc or wheel —25—.

For example assuming that the clock actuated wheel —31— is in the position shown in Figure —3— with the minute 110 hand indicating the hour, at which time the detent —26— will be in the notch —a—, then as cam wheel —31— continues to rotate on through its first quarter turn in the direction indicated by arrow "Y", the 115 arm —32— adjacent to the lever —29— will affect the movement of said lever a sufficient distance to trip the detent —26— but not until approximately the end of the first quarter turn of the cam wheel, because the arms —32— are so arranged with reference to the shoulder —33— on the lever —29— to cause but a very slight movement of said lever during the major portion of each quarter turn of the cam wheel while 120 the final tripping movement does not take place until the shoulder —33— is forced by the cam wheel —31— close to the end of the arms —32—.

Immediately following the tripping of 130

the detent —26— the chime mechanism is set in motion by the motor —9— and continues its operation until the next succeeding notch —b— is registered with the detent, which will then enter that notch and temporarily stop further the rotation of the gear train —8— and chimes until again tripped by the next succeeding arm of the cam wheel at the end of the next quarter hour, it being understood after each tripping operation the lever —29— is restored to its normal position shown by full lines, Figure —3—.

The space between the notches —b— and —c— being substantially twice the length of the space between the —a— b—, it is evident that the chimes will be operated continuously for a period twice as long as the first operation.

In like manner the chimes will be operated at the third and last quarter of the hour, the continued operation at the end of the third quarter being for a period three times as long as that of the end of the first quarter, while that for the fourth and last quarter will be for a period four times as long as that for the first quarter, and at the end of the last quarter the detent —26— will have entered the notch —a—, thus completing the cycle of operation of the chimes for one hour, which is repeated for each hour so that the length of time of operation of the chimes audibly indicates the quarter, half, three-quarters, and hour for each hour of time of the day.

What I claim is:—

1. A chime attachment for clocks comprising an upright frame having its upper end provided with means for attachment to the lower end of a clock frame, a charm-bar support on the first named frame near the lower end thereof, a series of chime bars secured at their lower ends to said support and extending upwardly some distance above the upper end of the first named frame, strikers, one for each bar mounted on the first named frame and extending upwardly along their respective charm bars for striking the same, rotary actuators, one for each striker, motor driven means separate from the clock for rotating and controlling said actuators and including a stop wheel and an escapement wheel, a rock shaft having a pair of pawls movable thereinto and out of engagement with the stop wheel and the escapement wheel respectively, an additional rock shaft having a tripping lever adapted to be engaged and operated by a cam wheel on the minute spindle of the clock, said additional shaft being provided with a pawl movable into and out of engagement with the escapement wheel, and means on the tripping lever for engaging and tripping one of the first named

pawls and thereby to rock the first named shaft for tripping the other of the first named pawls.

2. A chime attachment for clocks comprising an upright frame having its upper end provided with means for attachment to the lower end of a clock frame, a charm-bar support on the first named frame near the lower end thereof, a series of chime bars secured at their lower ends to said support and extending upwardly some distance above the upper end of the first named frame, strikers, one for each bar mounted on the first named frame and extending upwardly along their respective charm bars for striking the same, rotary actuators, one for each striker, motor driven means separate from the clock for rotating said actuators, said means including a stop wheel and an escapement wheel, a tripping lever adapted to be operated by a cam wheel on the minute spindle of the clock and provided with a pawl cooperating with the escapement wheel for controlling the operation of the motor driven chime actuators, a detent cooperating with the stop wheel to additionally control the operation of said chime actuators, means on the tripping lever for operating the detent, a rock shaft actuated by said detent, and an additional pawl actuated by the rock shaft and cooperating with the escapement wheel to further control the operation of the chime actuators.

3. The combination of a clock mechanism having its minute spindle provided with a cam wheel, and a supporting frame for the clock mechanism, of a chime operating mechanism and a separate supporting upright frame therefor having its upper end provided with means for attachment to the lower end of the clock frame, said chime mechanism including an escapement wheel, a charm-bar support mounted on the second named frame, charm bars secured at their lower ends to said support and extending upwardly some distance above the second named frame, and a pawl fulcrumed on the second named frame and having one end cooperating with the escapement wheel to control the operation of the chime actuating mechanism and its other end projecting into the path of movements of the cams of the cam wheel.

4. The combination with a clock mechanism having an upright frame, a minute spindle and a cam on the minute spindle, of a supplemental upright frame having means at its upper end for attachment to the lower end of the clock frame, a vertically adjustable charm-bar support mounted on the supplemental frame near the lower end thereof, charm bars secured at their lower ends to said support and extending upwardly some distance above the supplemental frame,

strikers pivotally mounted on the supplemental frame, a motor on the supplemental frame, mechanism actuated by the motor for operating the strikers, and means controlled by the cam-wheel on the minute spindle for controlling the operation of the striker-operating mechanism.

In witness whereof I have hereunto set my hand this 15th day of February 1919.

WILLIS H. ALLEN.
